(57) **CLAIM**

The ornamental design for an electronic hookah, as shown and described.

DESCRIPTION

FIG. 1 is a top, front, left side perspective view of an electronic hookah, showing my new design;

FIG. 2 is a bottom, front, right side perspective view of the electronic hookah, showing my new design;

FIG. 3 is a front view of the electronic hookah of FIG. 1, showing my new design;

FIG. 4 is a rear view of the electronic hookah of FIG. 1, showing my new design;

FIG. 5 is a right side elevation view of the electronic hookah of FIG. 1, showing my new design;

FIG. 6 is a left side elevation view of the electronic hookah of FIG. 1, showing my new design;

FIG. 7 is a top plan view of the electronic hookah of FIG. 1, showing my new design; and,

FIG. 8 is a bottom plan view of the electronic hookah of FIG. 1, showing my new design.
The broken lines in the drawings depict portions of the electronic hookah that form no part of the claimed design.

1 Claim, 7 Drawing Sheets
